(57) **CLAIM**

The ornamental design for a sliding drawer as shown and described.

DESCRIPTION

FIG. 1 is a perspective view of a sliding drawer, showing my new design in a first configuration of use in a retracted position;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of detail 8 in FIG. 6;

FIG. 9 is an enlarged view of detail 9 in FIG. 6;

FIG. 10 is a perspective view shown in a second configuration of use in the retracted position;

FIG. 11 is a perspective view shown in a third configuration of use thereof; and,

FIG. 12 is a perspective view shown in a fourth configuration of use in an extended position.

The broken line portions of the sliding drawer in FIGS. 1-12 represent unclaimed portions of the claimed design and form no part thereof.

1 Claim, 10 Drawing Sheets
